UNITED STATES PATENT OFFICE.

GEORGE C. TEWKSURY, OF NEWARK, NEW JERSEY.

AUTOMATIC ELEVATOR.

SPECIFICATION forming part of Letters Patent No. 264,793, dated September 19, 1882.

Application filed July 31, 1882. (No model.)

To all whom it may concern:

Be it known that I, GEORGE C. TEWKS-
BURY, of Newark, in the county of Essex and
State of New Jersey, have invented a new and
5 useful Improvement in Automatic Elevators;
and I do hereby declare that the following is
a full, clear, and exact description of the same.

My invention relates to an improvement in
automatic lifts or elevators of the class for
10 which Letters Patent were granted me on the
14th day of March, 1882.

The invention consists in an improved de-
vice for operating the shipping-rod and for
setting the parts in position to stop the ele-
15 vator automatically at its proper destination.

The invention is illustrated in the accom-
panying drawings, in which Figure 1 is a side
elevation; Fig. 2, a plan of rack and pinion
on an enlarged scale. Fig. 3 is a detail view
20 of Fig. 1, enlarged.

The general features of this device are the
same as those described in the patent re-
ferred to.

A represents a guide-bar on one side of the
25 elevator-well, in which slides the lift or plat-
form, it being understood that there are two
of such guide-bars placed on opposite sides of
the well.

C is the shipping-rod, which extends the
30 entire length of the well, and is adapted to
have vertical and rotary motion. It is guided
in its vertical movement by standards D, se-
cured to the guide-bars. It is understood
35 that at its upper end this rod is connected
with the shipping-bar by bolts in the manner
described in my patents; but it has been
deemed unnecessary to show these connec-
tions in this application, which refers to a
40 different portion of the apparatus. The rod is,
however, balanced by a counter-weight, 8, as
shown. The starting-lever 5 is pivoted to the
guide-bars A, and is connected by toggles Y to
a loose collar, I, upon the shipping-rod C.
45 This collar is held in place between two tight
collars, E E, on the said rod, and it will be
understood that the vertical movement of the
rod C is given to it by a direct pressure of the
hand on the lever 5.

Secured to the guide-bar A is a frame or
50 standard, K, and on this standard are bear-

ings O O, which form guides in which slides
the rack P. This frame is provided with an
integral curved projection or arc, N, which
arc is graduated by lines R, each of which
represents a single floor of the building. On 55
the frame K is a stud or standard, 4, to which
is pivoted the handle M. At a point near the
pivot this handle is enlarged, and is provided
with a slot, 3, which works over a pin, 2, on
the rack. Motion of the handle M around the 60
graduated arc will thus cause the rack to re-
ciprocate horizontally and to give the neces-
sary rotation to the rod C by means of the pin-
ion F, which is keyed or otherwise secured
thereto. Upon the rod C are tappets H, one 65
being placed at each landing, and all of such
tappets being set at different angles. On the
elevator-platform B is a dog, 7, adapted to
project outward to engage with the tappets on
the rod C. 70

It will be understood that the tappets on the
rod C are arranged in proper relation to the
graduated scale on the arc, so that the opera-
tion of the device is as follows: The operator
turns the handle M in line with the proper
75 mark on the scale, corresponding motion be-
ing given to the rack through the pinion to
the rod, which is thereby turned a sufficient
distance to bring the corresponding tappet in
line with the dog 7 on the elevator. The rod 80
C is then moved vertically through the lever
5, as described, which shifts the belts and
causes it to ascend or descend, as the case may
be, until its course is arrested by the dog 7
striking the tappet on the rod at the proper 85
destination of the elevator.

What I claim is—

1. In an automatic elevator, the combination,
with the guide-bars A and the shipper-rod C,
having the pinion F and tappets H, the frame 90
K, secured to the guide-bar, and having the
rack engaging with the said pinion, the piv-
oted handle M, attached to said rack, and the
indicating-scale, all substantially as described.

2. The combination of the guide-bars A and 95
the shipper-rod C, adapted to slide vertically
therein, the tight and loose collars E I, and
the lever 5, pivoted to the said guide-bar and
connected to the loose collar I, substantially
as described. 100

3. The frame K, secured to the guide-bar and having the standard 4, and graduated arc N, in combination with the shipper-rod having the pinion, the rack P, having the pin 2, and 5 the slotted handle M, pivoted to the said standard, substantially as and for the purposes set forth.

In testimony whereof I have signed my name

to this specification in the presence of two subscribing witnesses.

GEO. C. TEWKSURY.
